UNITED STATES PATENT OFFICE.

HORACE BENJAMIN BLOOD, OF ROCHESTER, NEW YORK.

SWAGE-BLOCK.

SPECIFICATION forming part of Letters Patent No. 727,885, dated May 12, 1903.

Application filed October 3, 1902. Serial No. 125,765. (No model.)

To all whom it may concern:

Be it known that I, HORACE BENJAMIN BLOOD, a citizen of the United States, and a resident of Rochester, in the county of Monroe and State of New York, have invented a new and Improved Swage-Block, of which the following is a full, clear, and exact description.

The invention relates to swage-blocks such as shown and described in Letters Patent of the United States No. 700,724, granted to Benjamin F. Blood on May 27, 1902.

The object of the invention is to provide a new and improved swage-block designed for the use of blacksmiths and other iron-workers and arranged to permit of securely clamping the anvil in the desired position and to allow of a quick release of the anvil whenever it is desired to adjust the anvil to a different position.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement. Fig. 2 is a plan view of one end of the improvement, parts being shown in section. Fig. 3 is a perspective view of part of the clamping device. Fig. 4 is a side elevation, partly in section, of a modified form of the improvement. Fig. 5 is a similar view of another modified form of the improvement. Fig. 6 is a like view of another modified form of the improvement. Fig. 7 is an end view of the anvil; and Fig. 8 is a perspective view of a modified form of the clamping device, the handle being shown detached.

The anvil or swage-block A is of usual construction and provided with suitable openings, recesses, or notches for selection by the mechanic, according to the nature of the work under treatment, and the ends of the said anvil are provided with trunnions or journals B B', engaging open bearings C C', formed or secured on the top of standards D D', connected with each other at their lower ends by rods E, as plainly shown in Fig. 1. A clamp-

ing device connects the standards D and D' with each other between the upper and lower ends thereof, so as to allow of drawing the upper ends of the standards toward or from each other for clamping the swage-block or anvil A in position or releasing the same for turning the anvil to a desired position.

The standards D and D' are provided at their inner faces, adjacent to the bearings C and C', with transverse flanges D² and vertical recesses D³ for engagement by the ends of the anvil to hold the same in either a horizontal or vertical position at the time the standards D and D' are drawn together by the clamping device, the same as shown and described in the Letters Patent above referred to, so that further description thereof is not deemed necessary.

The rod F of the clamping device carries at one end a crank arm or handle G under the control of the operator, and on the other end of the rod is formed a screw-thread F', screwing in a nut H', the rod passing loosely through a bearing H. The bearing H and nut H' are removably held in the cross-bars D⁴ D⁵ of the standards D and D', the said bearing and nut being provided with notches fitting into forks in the cross-bars to hold the bearing and nut against longitudinal movement, but to allow of lifting them out of the cross-bars whenever it is desired to disconnect the clamping device from the standards. Now by turning the handle G in the proper direction a rotary motion is given to the rod F to screw the same in the nut H', and as the shoulder of the handle G comes in contact with the outer face of the bearing H the bearing and nut and consequently the standards D and D' are drawn toward each other.

In order to quickly release the ends of the anvil A from the standards D and D' at the time the upper ends thereof are moved apart, I interpose springs I and I' between the ends of the journals B B' and lugs C² C³, formed on the bearings C C', the outer ends of the springs I and I' being held on pins C⁴, projecting from the inner faces of the lugs C² C³, and the inner ends of the said springs are set in recesses formed in the ends of the trunnions or journals B B', as plainly indicated in Fig. 2. Now when the ends of the standards D D' are drawn together by a cor-

responding action of the clamping device then the springs I and I' are compressed and the pins C⁴ pass into the openings in the trunnions to hold the latter and consequently the anvil A against upward movement in the bearings C C'. As soon as the clamping device is actuated to move the upper ends of the standards D D' apart then the springs II' exert their pressure on the trunnions and standards to immediately disengage the ends of the anvil from the inner faces of the standards to allow convenient turning of the anvil to another position. This result may also be obtained by other means—for instance, as shown in Fig. 4, by the use of flanges B³, formed on the ends of the trunnions or journals B², the said flanges being adapted to engage shoulders D⁶ on standards D⁷, so that when the standards move apart the corresponding shoulder D⁶, engaging a flange B³, pulls the anvil A' with it, so as to move the opposite end of the anvil out of engagement with the opposite standard. The end of the journal B² is formed with an opening B⁴, adapted to be engaged by a pin C⁴ on a lug C⁵, either integrally formed on the standard D⁷, as shown in Fig. 4, or bolted thereto, as indicated in Fig. 6.

In the modified form shown in Fig. 5 the anvil A² is formed with conical trunnions B⁵, engaging correspondingly-shaped bearings C⁶ on the standards D⁸, so that when the upper ends of the standards are moved apart the trunnions slide down the bearings C⁶, thus moving the ends of the anvil out of contact with the inner faces of the standards. When the upper ends of the standards D⁸ are drawn together, then the trunnions B⁵ rise, and their apex ends engage lugs C⁷, formed on the bearings C⁶ to hold the trunnions, and consequently the anvil, against upward movement.

The clamping device shown in Fig. 8 consists of a rod F², having one end F³ polygonal and secured in a corresponding opening in the cross-bar D⁹ of one of the standards by heads F⁴, held on the said end F³ and abutting against the faces of the said cross-bar. The other end F⁵ is threaded, and on this end screws a handled nut G', under the control of the operator and arranged to abut against the outer face of the other cross-bar D¹¹ on the opposite standard, and the said end F⁵ extends through an elongated aperture D¹⁰ in the said cross-bar. A spring J is coiled on the threaded end F⁵ and rests with one end on a collar F⁶, secured to the rod F², the other end of the spring abutting against the inner face of the cross-bar. Now by screwing up the nut G' on the end F⁵ against the cross-bar D¹¹ the standards are drawn toward each other, and at the same time the spring J is pressed, and when the nut G' is screwed outward on the end F⁵ then the standards are pressed apart by the action of the spring J.

Having thus described my invention, I claim as new and desire to secure by Letters Patent—

1. A device of the class described, comprising a frame having standards connected with each other at their lower ends, open bearings in the upper ends of the said standards, an anvil having journals engaging the said open bearings, a clamping device for moving the upper ends of the standards toward each other, to engage the standards with the ends of the anvil, and resilient means for separating the standards and the ends of the anvil on opening the clamping device to permit the anvil to turn freely on its trunnions, as set forth. 80

2. A device of the class described, comprising a frame having standards connected with each other at their lower ends, open bearings in the upper ends of the standards, an anvil having journals engaging the said bearings, a clamping device for moving the upper ends of the standards toward each other, to engage the standards with the ends of the anvil, a retaining device on the standards, adapted to engage the journals, to hold the latter against upward movement in their bearings at the time the upper ends of the standards are drawn toward each other, and resilient means for separating the standards and the ends of the anvil, when the clamping device is actuated to release the anvil, thereby permitting the anvil to turn freely on its trunnions, as set forth. 95

3. A device of the class described, comprising a frame having standards connected with each other at their lower ends, open bearings in the upper ends of the standards, an anvil having journals engaging the said bearings, a clamping device for moving the upper ends of the standards toward each other, to engage the standards with the ends of the anvil, and springs interposed between the ends of the journals and the upper ends of the standards, to move the anvil out of engagement with the standards on opening the said clamping device, as set forth. 100

4. A device of the class described, comprising a frame having standards connected with each other at their lower ends, open bearings in the upper ends of the standards, an anvil having journals engaging the said bearings, a clamping device for moving the upper ends of the standards toward each other, to engage the standards with the ends of the anvil, springs interposed between the ends of the journals and the upper ends of the standards, to move the anvil out of engagement with the standards on opening the said clamping device, the inner ends of the said springs being set in openings in the ends of the journals, and pins carried by the standards, adapted to engage said openings, to hold the trunnions against upward movement in the bearings, as set forth. 115

5. A device of the class described, comprising a frame having standards connected with each other at the bottom and provided with cross-bars between their upper and lower ends, an anvil journaled in the upper ends 120

of the standards, and a clamping device engaging notched bearings in the cross-bars and adapted to be lifted therefrom, as set forth.

6. A device of the class described, comprising a frame having standards connected with each other at the bottom, an anvil journaled in the upper ends of the standards, and a clamping device having a removable connection with the standards, between the upper 10 and lower ends thereof, the said clamping device comprising a screw-rod under the control of the operator, a notched bearing through which the rod passes, and a notched nut engaged by a screw-thread on the rod, the said bearing and nut being removably held in the standards, as set forth.

7. A device of the class described comprising a frame having standards connected with each other at the bottom, an anvil journaled 20 in the upper ends of the standards, a clamping device for moving the upper ends of the standards toward each other to engage the standards with the ends of the anvil, and springs compressed when the standards are

drawn toward each other and adapted by their 25 expansion to disengage the standards from the end of the anvil, when the clamping device is opened, as set forth.

8. A device of the class described comprising a frame having standards connected with 30 each other at their lower ends, open bearings in the upper ends of the said standards, an anvil having journals engaging the said open bearings, a clamping device for moving the upper ends of the standards toward each 35 other to engage the standards with the end of the anvil, and lugs on the standard provided with projections adapted to engage openings in the trunnions of the anvil, for the purpose set forth.

In testimony whereof I have signed my name to this specification in the presence of two subscribing witnesses.
